UNITED STATES PATENT OFFICE.

THOMAS H. BARRY, OF EMPIRE, OREGON.

WRENCH.

SPECIFICATION forming part of Letters Patent No. 756,565, dated April 5, 1904.

Application filed June 27, 1903. Serial No. 163,344. (No model.)

To all whom it may concern:

Be it known that I, THOMAS H. BARRY, a citizen of the United States, and a resident of Empire, in the county of Coos and State of Oregon, have invented a new and Improved Wrench, of which the following is a full, clear, and exact description.

This invention relates to a class of wrenches having a fixed jaw on the end of a handle-lever, a sliding jaw on the lever, and means for holding the sliding jaw at a selected point on the lever.

The object of the invention is to provide novel details of construction for a wrench of the indicated class, which afford a very convenient implement, capable of receiving instant adjustment, adapted for automatic closure, and which will operate reliably at any point of opened adjustment.

The invention consists in the novel construction and combination of parts, as is hereinafter described, and defined in the appended claims.

Reference is to be had to the accompanying drawings, forming a part of this specification, in which similar characters of reference indicate corresponding parts in all the figures.

Figure 1 is a perspective view of the improved wrench. Fig. 2 is a longitudinal sectional view showing interior details. Fig. 3 is a perspective view of the slidable jaw and the adjusting-rack carried by said jaw, and Fig. 4 is a perspective view of a spring-dog that is a detail of the invention.

The lever 5, which is of suitable length proportioned to conform with the desired capacity of the tool, is rectangular in cross-section and at one end is provided with a fixed jaw 6, disposed transversely, as usual. A shank 5^a is formed on the handle-lever 5 by reduction of the width of said bar, that produces a shoulder *a* thereon at a suitable distance from the end of the shank, which distance is preferably equal in length to that of the handle-block or grip-piece 7, which may be of wood or metal.

A slidable jaw is furnished as a wrench member complementary to the fixed jaw 6,

and comprises a jaw-limb 8 and a rectangular loop 8^a, the opening in the latter being of such dimensions and form as will permit the body of the handle-lever 5 to fit loosely therein and adapt the looped jaw to slide on the lever. From the jaw-limb 8, adjacent to the rectangular loop 8^a, a rack-bar 9 extends at a right angle to the working face of the jaw, and upon the edge of the rack-bar opposite the one which contacts with the handle-lever when the parts of the wrench are assembled a series of rectangular rack-teeth *b* is formed, that extend from the end of the rack-bar toward the integral jaw-limb 8.

The grip-piece or handle proper for the wrench consists of a rounded and suitably-elongated block 7, through which an aperture *c* is formed to receive the shank 5^a, that fits neatly therein, and it will be seen that when the shank is fully inserted into the handle-block the shoulder *a* will impinge upon the inner end of the handle-block and the end of the shank become flush with the outer end of the handle. It may here be explained that if the handle-block is of hard wood a washer-plate 10 may be embedded in one side thereof, having holes formed therein at proper points for the passage therethrough of screws or rivets *d*, that also pass through aligned perforations *e*, formed in the shank 5^a and the handle-block, and when inserted serve to secure the handle upon the shank of the handle-lever 5.

In the handle-block 7, parallel with and adjacent to the longitudinal aperture *c*, a passage *c'* is formed, this passage being adapted to receive the portion of the bar 9 whereon the teeth *b* are formed. The passage *c'* does not extend entirely through the handle-block 7, but affords a chamber *c''*, extending from the inner extremity of the rack-bar 9, wherein a coiled spring 12 is placed. Two studs *g* *g'* are formed, respectively, on the inner end of the rack-bar 9 and the end wall of the chamber *c''*, these studs entering the ends of the spring 12, so as to hold the latter in position

for the exertion of direct pressure on the rack-bar, which will be forced by the spring toward the fixed jaw 6, so as to impinge the jaw 8 thereon, this occurring when the spring 5 is permitted to expand freely.

The preferred means for detachably securing the jaw 8 at any point of retracted adjustment consists in the provision of a spring-dog, which, as shown in Figs. 2 and 4, consists of a preferably curved resilient arm 13, fitted upon the handle-block 10, whereon it is secured by one end, as shown at *h* in Figs. 1 and 2, said arm at its opposite end having a toothed dog 14 projected laterally therefrom, 15 which loosely occupies an opening *i*, formed in the handle-block opposite the rack-teeth *b*.

The "set" of the spring-arm 13 is such that the dog 14 is normally pressed toward the teeth *b* on the rack-bar 9 and engages its teeth 20 *b'* between the teeth opposite which it may lie. On the end of the arm 13 adjacent to the dog 14 a catch-lip *m* is formed, that is shaped for convenient manipulation to press it outward, and thus remove the teeth *b'* from 25 engagement with the rack-teeth *b*, as indicated by dotted lines in Fig. 2. As shown in Fig. 2, the jaw-limb 8 projects at its free end slightly beyond the adjacent end of the fixed jaw 6, so as to provide an offset *n*.

30 When the wrench is to be adjusted to engage an object, such as a screw-nut or the head of a bolt between the jaws 6 and 8, assuming that the slideable jaw is in closed adjustment; the wrench is grasped by its handle 7 and the 35 slideable jaw at the offset *n* is pressed upon a fixed object—such, for example, as a nut that the wrench is to be adjusted to receive between its jaws. Pressure is now applied simultaneously with the manipulation of the catch-lip *m* for release of the dog 14 from the rack-teeth *b*, whereupon the jaw 8 will be pressed 40 away from the jaw 6 a desired distance, thus compressing the spring 12. Then a release of the catch-lip will permit stress of the spring-arm 13 to press the teeth *b'* of the dog 14 into engagement with the teeth *b* on the rack 9, and thus lock the rack-bar and jaw thereon at 45 a desired point of retracted adjustment.

As the teeth *b b'* are parallel on their sides 50 when they are engaged, a positive lock of the jaw 8 is effected, so that the wrench may be used with full effect for turning an object with which it may be engaged.

Obviously the release of the dog 14 by manipulation of the catch-lip *m* will permit stress 55 of the spring 12 to expand and force the jaw

8 into contact with the jaw 6 or into closed condition.

Having thus described my invention, I claim as new and desire to secure by Letters Patent— 60

1. The combination with a handle-lever having a fixed jaw at one end, and a shank at the opposite end that is reduced in width affording a shoulder, of a jaw mounted to slide upon the handle-lever, a rack-bar extended from the 65 slideable jaw and having teeth on one edge near its free end, a handle-block apertured to receive the shank and abutting against the shoulder thereon, means for securing the handle-block upon the shank, said block having a longitudinal chamber therein which receives the toothed portion of the rack-bar, a resilient arm attached by one end upon the outer side of the handle-block and projecting above the rack-teeth, a toothed dog on the free end of 70 the resilient arm adapted to mesh with the teeth on the rack-bar, and means for manual release of the dog therefrom.

2. The combination with a handle-lever having a fixed jaw on one end, and a shank on the 80 opposite end thereof reduced in width, affording a shoulder, of a slideable jaw mounted upon the handle-lever and having its free end projected therefrom farther than the fixed jaw, a rack-bar extended from the slideable jaw and 85 having teeth on one edge near its free end, said teeth having parallel sides, a handle-block longitudinally apertured to receive the shank of the lever and abutting upon the shoulder thereon, the handle-block and shank having 90 a plurality of perforations, screws engaging said perforations, the block having a longitudinal chamber parallel with the aperture therein, said chamber at one end receiving the toothed end of the rack-bar, an expandable 95 spring in the chamber, pressing upon the end of the rack-bar, and a locking device comprising a curved resilient arm secured by one end on the end of the handle-block, a laterally-projected dog at the other end of the arm, 100 said dog having teeth and projecting through an opening in the handle-block for engagement of its teeth with the rack-bar teeth, and a catch-lip on the resilient arm adjacent to the dog. 105

In testimony whereof I have signed my name to this specification in the presence of two subscribing witnesses,

THOMAS H. BARRY.
